UNITED STATES PATENT OFFICE.

JULIUS CARL SIEGFRIED KOCH, OF HAMBURG, GERMANY.

GAS BURNER FOR HEATING AND COOKING PURPOSES.

Application filed February 7, 1925. Serial No. 7,567.

To all whom it may concern:

Be it known that I, JULIUS CARL SIEGFRIED KOCH, a citizen of Hamburg, Germany, residing at Hamburg, Germany, have 5 invented certain new and useful Improvements in a Gas Burner for Heating and Cooking Purposes, of which the following is a specification.

The present invention refers to a gas- 10 burner for heating and cooking purposes which, as has been proved by scientific investigations, is distinguished from burners known heretofore by its extraordinary efficiency. By a model it has been proved that 15 the highest degree of efficiency is 72.18%. In the new burner the mixture produced in a known manner by a vertical mixing nozzle is led close up to the table of the burner whereupon it is expanded by radial exit 20 openings to a disk-like plane by additional air being added. The novelty resides in that the mixture of gas before being ex- 25 pelled from the radial apertures passes across the mouth of an annular space inter- mediate the feed pipe and the mantle of the burner head, the additional air being fed to the annular space at a given distance below the outlet apertures. The mantle sur- 30 rounding the feed pipe for a certain dis- tance is provided on its outer surface with broad outlet slits. The flame thus produced will have a diameter of from 20 cm. up, so that a single burner will be sufficient to 35 heat even large pots and other vessels, as for instance copper boilers.

An embodiment of the invention is shown with accompanying drawings wherein:

Fig. 1 shows a burner constructed accord- 40 ing to the present invention, in elevation, the protecting hood being shown in section.

Fig. 2 is a vertical section, and

Fig. 3 is a horizontal section on the line 3—3 of Fig. 2.

The gas is fed in by the pipe 1 and enters 45 the burner by the first nozzle 2 mixing with the air entering the burner by the openings 3 which preferably rise at an angle in- wardly and upwardly. The gas mixture thus produced passes through a second nozzle 4 and is again mixed with air entering by openings 5. The thus dilated gas mixture is fed into a central tube 6 of com- paratively large diameter opening out close to the inner face of a table 7 of the burner 50 head. This table is mounted on a mantle 9 having broad outlet slits 8. Intermediate

the mantle 9 and the tube 6 is an annular space, the mantle being held in proper position by strips 10. An additional amount of air is allowed to pass into the space between 60 the tube 6 and the mantle 9 by apertures 11. This air flowing upwardly in the annular space will be preheated by the mantle 9 of the burner head which is itself very hot.

The mixture produced by the nozzles 2 65 and 4 will spread disk-like to the sides on striking the table 7 and over the rim of the tube 6, and before leaving the burner by the broad slits 8 will be given an additional amount of preheated air moving at right angles to the plane of the table 7 which air on account of meeting the gas mixture at right angles will intimately mix with this gas mixture. The flame produced by the burner is subjected to a very high pressure, and therefore will spread out to a great 70 degree.

It may be advisable to construct the mantle to have the openings or slits 8 slidably 75 adjustable in a vertical direction, so as to allow the flame to approach the cooking pot more or less in a manner known per se. Such adjustability will be advisable for regulating the heat and for avoiding burn- 80 ing the food.

The raising and lowering of the mantle 85 can be carried out by the aid of an imple- ment of any desired construction, such for instance as a wedge to be inserted at the meeting line 13 between the mantle 9 and the lower part 12 of the burner. In the construction shown the raising and lower- 90 ing of the mantle 9 can be carried out by a double-armed lever 15 pivoted at 14 to the lower part 12 of the burner. This lever 95 is articulated to a rod 16 and is adapted to engage a pin 18' on the mantle 9 by a slot 17' arranged on the free end of the upper arm of the said lever. By recipro- 100 cating the rod 16 the mantle 9 can be raised and lowered at will. When the mantle is thus raised the slits or openings 11 are enlarged.

On the outside of mantle 9 a conical pro- 105 tection hood or guard 17 is mounted outside, which prevents contact of the flame at the slits 8 with the air entering the openings 11 and with the air entering the openings 5 or 3 with resulting production of flames and pushing back of the incoming gases. 110

I claim:

1. A gas burner for heating purposes,

- comprising, a mantle, a horizontal spreading table supported by the mantle, radial gas outlets in the mantle and immediately below the table, a tube positioned within and spaced from the mantle to leave an annular space therebetween, air inlets in the mantle, the upper end of the tube being open and terminating adjacent the table, a mixing nozzle positioned to feed into the lower end of the tube whereby the mixture from the mixing nozzle is forced to spread out upon meeting the table and to pass across the mouth of the annular space before passing out through the radial gas outlets.
2. A gas burner according to claim 1, said air inlets in the mantle being positioned adjacent the plane of the base of said tube.
3. A gas burner according to claim 1,

said radial gas outlets being relatively long horizontal slits.

4. A gas burner for heating purposes, comprising an outer mantle, a horizontal spreading table supported by the mantle, radial gas outlets in the mantle and immediately below the table, a tube positioned wholly within and spaced from the mantle to leave an annular chamber therebetween, air inlets in the mantle communicating with the annular chamber, the upper end of the tube being open and terminating immediately adjacent the table, and a mixing nozzle positioned within the mantle to feed into the lower end of the tube.

5. A gas burner according to claim 4, said air inlets in the mantle being positioned adjacent the plane of the base of said tube.

JULIUS CARL SIEGFRIED KOCH.
